APPARATUS FOR TREATING GARBAGE AND
THE LIKE WASTE MATERIALSKai Petersen, Soborg, near Copenhagen,
DenmarkApplication December 27, 1939, Serial No. 311,189
In Great Britain January 19, 1939

15 Claims. (Cl. 83—9)

1

My present invention relates to an apparatus for treating garbage and the like waste materials containing difficultly grindable and/or non-grindable components.

More particularly, my invention constitutes an improvement in the apparatus described in my copending application Serial No. 261,631 filed March 3, 1939, and which became Patent No. 2,252,520 on August 12, 1941. In this apparatus garbage is converted into a substantially homogeneous, granular and fibrous mass by treating the garbage in rotary grinding drums containing one or more grinding chambers, the circumferential walls of which are constructed as a grid or a coarse screen surrounded by a finer screen having a mesh determining the fineness of the sufficiently ground material. At the same time a waste product is produced which consists of the difficultly grindable and/or non-grindable components of the garbage and which is referred to in the following as the "waste" or "remnants."

The main object of my present invention is to provide an apparatus in which it is possible to bring the coarse matter of the waste or remnants out of the grinding chamber or chambers without affecting the useful operation of the apparatus and to govern the movement and travel of the waste and the other components through the apparatus.

Broadly speaking, this object is accomplished by providing in the coarse screen or grid forming the circumferential walls of the grinding chamber one or more apertures being larger than the normal openings of the said coarse screen or grid and allowing the coarse matter of the waste or remnants to leave the grinding chamber when occasionally meeting the said apertures. In other words, the coarse matter of the waste slips through the grid or coarse screen when the opportunity presents itself. In order to distinguish the normal openings of the grid or coarse screen from the large apertures thereof through which the coarse matter of the waste or remnants slips, the latter will be referred to in the following as "the slipping apertures."

A clear conception of the improvements according to my invention may be had by the following description containing a detailed explanation of my invention with reference to the accompanying drawings illustrating by way of example various preferred embodiments of apparatus and wherein:

Figure 1 is partly an elevation and partly a longitudinal sectional view of one embodiment.

Figure 2 is a cross-sectional view of the same on line II—II of Figure 1.

Figures 3 and 4 are developed views on an enlarged scale of one of the grid sections of the grinding chambers provided with slipping apertures of a modified construction.

2

Figure 5 is a cross-sectional view of another embodiment, the said view corresponding to that shown in Figure 2.

Figure 6 is a similar view as those shown in Figures 3 and 4 of a further embodiment in which the circumferential walls of the grinding chambers are constructed as a coarse screen.

The apparatus shown in Figures 1 and 2 comprises a rotatable grinding drum having two end plates 1 and 3. A hollow trunnion 5 is secured to the end plate 1 and journaled in a bearing 7. A toothed ring 9 is also secured to the end plate 1 and adapted to be driven by a pinion not shown. Connecting braces or spider arms 11 make the construction sufficiently rigid. Instead of the ring 9 a pulley may be secured to the end plate 1 so that the drum may be belt driven.

To the other end plate 3 there is secured a bearing ring 13 which rests on rollers 15, one of which is shown in Figure 1. The rollers 15 are journaled in bearings 17. The end plate 3 is provided with a central aperture 19 receiving the lower part of a stationary hopper 21.

The grinding drum is divided into two grinding chambers or compartments 23 and 25, respectively, by means of an elevating device 27 which is rigidly secured to double channel irons 29 being equidistantly spaced circumferentially and secured at their ends to the end plates 1 and 3, respectively. Together with angularly bent grid bars 31 spaced and secured to the inner flanges of the said channel irons, the channel irons form the circumferential walls of each grinding chamber 23 and 25, the said walls thereby constituting a grid provided with stepped surfaces the normal openings of the said grid having such a size as will prevent the coarse, difficultly grindable and/or non-grindable components of the garbage forming the waste or remnant from leaving the grinding chambers. Thus, the circumferential walls of the grinding chambers have the form of a grid divided by the channel irons 29 into sections the number of which depends on the number of channel irons. In Figures 1 and 2 each grinding chamber contains 12 grid sections.

At various places of the grinding chamber 23 the grid bars 31 are arranged with relatively large spaces forming larger apertures 22 through which the coarse matter of the waste or remnants may slip. The same applies to the grinding chamber 25 in which the slipping apertures are indicated by 24.

Both grinding chambers 23 and 25 are surrounded by conical screens or sieves 33 having a mesh determining the fineness of the sufficiently ground material and being finer than that of the grid forming the circumferential walls of the grinding drum. Hereinafter they will be referred to as "fine sieves" although they are only relatively fine, having for instance a width of about

1 cm. Bracing bars 35 are secured to the screens or sieves 33 as shown in Figure 1.

At the outlet end of the grinding chamber 25 there is arranged an elevating device 37 in a similar manner as the elevating device 27. At the circumference of each elevating device there are secured longitudinal blades 39 being equidistantly spaced circumferentially and secured at one end to braces 41 connected with a collar 43 encircling and secured to the front end of the fine sieve 33 surrounding the grinding chamber 23.

The elevating device 27 being rigidly secured to the grinding drum, for instance welded thereto, and having a larger diameter than that of the grinding chambers consists of a casing formed by side walls 45 and 47 and a circumferential wall 49 secured to the said side walls. By means of parallel transverse partitions 51 and 53 there are provided tube-like passages 55, of which four are shown in Figure 2. Through inlet openings formed by apertures 57 provided at the circumference of the side wall 45 the passages 55 communicate with the space inside the fine sieve 33. At the trailing edge of the aperture 57 a guiding blade 59 is secured to the side-wall 45.

At the inner ends of the transverse partitions 51 and 53 an aperture or outlet opening 61 is provided in the side wall 45, a corresponding outlet opening being also provided in the side wall 47 and opposite to the outlet opening, the former being, however, not shown on the drawings. Through these outlet openings the passage 55 may communicate with the grinding chamber 23 or the grinding chamber 25. The inner portion of the passage 55 is limited by two abutting inclined plates 63 and 65. At the meeting edges of the inclined plates forming together a wedge a shaft 67 is journaled which carries a swingable member in the form of a flap valve 69. The shaft 67 extends laterally to the axis of the grinding drum and transversely to the longitudinal direction of the passage 55 to the circumference of the casing 27 where the said shaft is journaled in a bearing 71. To the outer end of the shaft 67 there is secured an arm 73, see Figure 1, having a stud 75 moving in a slit 77. By moving the arm 73 the shaft 67 and the valve 69 connected thereto may be turned. To each of the inclined plates 63 and 65 there is secured an inclined plate 79 extending to the side wall 45 or 47 and connected therewith.

The elevating device 37 at the outlet end of the grinding chamber 25 is constructed and arranged in the same way as the elevating device 27 with the exception that other means are used for turning the shafts of the flap valves 69. A slideable tube 81 extends through the hollow trunnion 5 of the grinding drum. To the inner end of this tube there is secured a transversely arranged head 83 connected by links 85 with crank arms 87 on the shafts of the flap valves 69. A non-displaceable bar 89, upon which the tube 81 may slide, extends through the same. The outer end of the bar 89 is journaled in a bearing 91 supported by a bracket 101. Moreover, the bar 89 is provided with a stop member 103 adapted to cooperate with a grooved collar 105 on the outer end of the tube 81 to limit the outward travel of the latter.

On the drawings no grinding bodies are shown although such are ordinarily used. However, they may be dispensed with when treating garbage and the like waste materials as it has been found that garbage is self-grinding. Thus, in small plants where only small capacities are re-

quired the grinding bodies may be dispensed with. However, when working on a large scale where high capacities are required a suitable number of grinding bodies, such as iron balls, is placed in the grinding chambers 23 and 25.

Garbage or the like waste material is supplied continuously to the grinding chamber 23 through the hopper 21 and the elevating device 27 is adjusted for transferring the material which can not pass through the fine sieve 33 to the grinding chamber 25 while the elevating device 37 is adjusted for returning the said material to the grinding chamber 25. The apparatus is rotated in the direction indicated by the arrow *a* in Figure 2.

Due to the presence of the slipping apertures 22 in the grid of the grinding chamber 23 such coarse matter of the waste or remnants as is unable to pass the normal openings of the grid, is discharged from the first grinding chamber and transferred to the second grinding chamber. The accumulation of waste or remnants occurring in the first grinding chamber when operating with a continuous supply through the hopper 21 is greatly decreased due to the presence of the slipping apertures and may according to the conditions and the shape of the said apertures be completely avoided. Thus, it is possible to operate with a continuous supply of raw material for a longer period than without the presence of slipping apertures.

The sufficiently ground material is sifted off by means of the fine sieves 33 surrounding the grinding chamber 23 while the mixture of waste or remnants and insufficiently ground material is transferred to the second grinding chamber 25 by means of the elevating device 27. Due to the slipping apertures 24 in the grinding chamber 25 such coarse waste as is unable to pass the normal openings of the grid of the said chamber, is carried out of the said chamber and discharged from the apparatus when the elevating device 37 is adjusted for discharging the said waste.

By means of the slipping apertures 22 and 24 it is possible during the operation of the apparatus to perform a more thorough discharge of the waste or remnants than that obtainable in the apparatus hitherto known for treating garbage and like waste material. Moreover, it is possible to perform an exhausting grinding in the chamber 25 and to discharge the waste or remnants from this chamber while supplying raw material to the grinding chamber 23.

Furthermore, the slipping apertures are also of consequence to the treating process itself which is effected in the grinding chambers. In order to convert garbage into a substantially homogeneous, granular and fibrous mass not only a grinding action, but also an intensive intermixing is to be performed. By means of the latter the relatively dry components of the garbage absorbs some of the moisture of the very moist components. Without this equalization of the moisture contents the finished product aimed at is not obtainable. For this reason and also for other reasons there is an upper limit for the size of the grid openings. On the other hand, too long a treating period of the garbage in the grinding drum without removing materials sufficiently ground, may cause the formation of a doughy mass. By means of the slipping apertures the amount of the material removed is increased without being detrimental to the necessary equalization of moisture. Finally, the presence of the coarse matter of the waste on the surface of the

5

fine sieves 33 facilitates the screening action and prevents clogging of the fine sieves.

Although I have obtained excellent results with the construction and arrangement of the slipping apertures shown in Figure 1 my invention is not restricted to this construction and arrangement particularly in view of the fact that the construction and arrangement of the slipping apertures largely depend on the character of the garbage to be treated.

For instance, the slipping apertures need not extend into the whole length of the grid sections. This is illustrated in Figures 3 and 4.

In Figure 3 the central portion of some of the grid bars 31' is removed so as to provide slipping apertures 22'. The ends of the bars 31' are secured to transversely extending bars 31'' which at their ends are secured to the continuously extending grid bars 31. Instead of being arranged in the middle of a section the slipping apertures 22' may be provided adjacent to the channel irons 29 for instance such as indicated at the bottom of Figure 3.

In Figure 4 each section only contains one slipping aperture 22'' which is provided in a similar manner as in Figure 3, but with its largest proportion in the longitudinal direction of the grinding drum in contradistinction to the slipping apertures 22'. Also the slipping aperture 22'' may be arranged at different places in adjacent sections, for instance such as indicated.

By substituting some of the slipping apertures 22 of the grinding chamber 23 of the apparatus shown in Figure 1 by the slipping apertures shown in Figure 3 and/or 4 a grinding chamber is obtained which contains slipping apertures of different size. If desired, the slipping apertures may also be arranged in groups instead of being spaced as shown in Figure 1 or some of them may be spaced and others arranged in groups.

In the apparatus shown in Figures 1 to 4 the slipping apertures are permanent. They may, however, also be so constructed that they are adjustable in that they may be either diminished or removed. This is illustrated in Figure 5 showing a cross-section of an apparatus otherwise constructed as that shown in Figures 1 and 2.

Some of the grid bars 31 are cut over at one end adjacent to the channel irons 29 and swingably mounted at the other end adjacent to the following channel irons 29 as indicated by 93. The free end of the grid bar thus formed is supported by a link 95 connected to a crank 99. By operating the said crank the grid bar may be turned into a position either in alignment with the adjacent grid bars or beneath the same. Both positions are shown in Figure 5.

In this or other similar manner obvious to those skilled in the art the size and number of the slipping apertures may be varied.

Instead of constructing the circumferential walls of the grinding chambers as a number of grid sections they may, as mentioned above, also be constructed as a coarse screen. This is illustrated in Figure 6.

Sections of coarse screen 107 are secured to the channel irons 29, for instance welded thereto, and provided with normal openings 109 having such a size as will prevent the coarse, difficultly grindable and/or non-grindable components of the garbage from leaving the grinding chamber but allow the fine and sufficiently ground matter together with partly ground material to pass. At various places larger apertures 111 are provided acting as slipping apertures through which the

6

coarse matter of the waste or remnants may leave the grinding chamber when the said matter occasionally meets the slipping apertures during the rotation of the apparatus.

Generally, I prefer to construct the circumferential walls of the grinding chambers as grids. The size of the normal openings of the grids depends on the character of the garbage to be treated and may be determined by experimental work considering the period of time to be used for grinding the material and for performing the screening action due regard also being paid to the composition of the material leaving the grinding chamber for screening on the fine sieves, to the number of times the material has to pass through the grid-shaped grinding surface for screening, and to the prevention of clogging of the grinding surface. I have found that in order to obtain a successful operation of the apparatus the normal openings of the grid may preferably have a length of about 600 to 700 millimetres and a width of about 18 to 30 millimetres while the useful sifting or screening area of the grid represents about 25 to 50% of the whole grinding surface. With the construction of the grid the coarse matter of the waste or remnants will not be able to pass the grid without providing slipping apertures. The length of the slipping apertures may be the same as that of the normal openings, preferably somewhat smaller while the width of the said apertures is preferably about 40 to 70 millimetres, their area in the highest representing 50%, preferably 10-30%, of the whole useful area of the grid. Moreover, as a general rule, it is not appropriate to provide slipping apertures adjacent to the places of the grinding chamber where material is returned to the said chamber.

I am aware that many changes may be made in the construction of the apparatus described above and as illustrated on the drawings while still retaining the general principles of my invention. Hence I do not limit my invention to the exact arrangements and construction of parts, as described in the foregoing specification, nor do I confine myself to the exact details of construction of the various parts as illustrated on the accompanying drawings.

I claim:

1. In an apparatus of the ball mill type for grinding garbage and the like waste materials, a rotary grinding chamber, a coarse screen forming the circumferential walls of the said chamber and acting as the grinding surface of the chamber, the said screen having a plurality of openings of such a size as will prevent the coarse, difficultly grindable and non-grindable components of the garbage from leaving the grinding chamber and in addition thereto having a considerably smaller number of large apertures arranged within the field of and being larger than the first mentioned openings of the screen, said apertures allowing the coarse, difficultly grindable and non-grindable components to leave the grinding chamber when they by chance meet with the said apertures and a fine screen for screening the material passing through the coarse screen, said fine screen having a mesh determining the fineness of the sufficiently ground material.
2. An apparatus as claimed in claim 1, in which the large apertures are of different size.
3. An apparatus as claimed in claim 1, in which the large apertures are spaced.
4. An apparatus as claimed in claim 1, in which the large apertures are arranged in groups.
5. In an apparatus of the ball mill type for

grinding garbage and the like waste materials, a rotary grinding chamber, a coarse grid forming the circumferential walls of the said chamber and acting as the grinding surface of the chamber, the said grid having a plurality of openings of such a size as will prevent the coarse, difficultly grindable and non-grindable components of the garbage from leaving the grinding chamber and in addition thereto having a considerably smaller number of large apertures arranged within the field of and being larger than the first mentioned openings of the grid, said apertures allowing the coarse, difficultly grindable and non-grindable components to leave the grinding chamber when they by chance meet with the said apertures and a fine screen for screening the material passing through the coarse grid, said fine screen having a mesh determining the fineness of the sufficiently ground material.

6. An apparatus as claimed in claim 5, in which the large apertures are of different size.

7. An apparatus as claimed in claim 5, in which the large apertures are spaced.

8. An apparatus as claimed in claim 5, in which the large apertures are arranged in groups.

9. In an apparatus of the ball mill type for grinding garbage and the like waste materials, a rotary grinding chamber, a coarse screen forming the circumferential walls of the said chamber the said screen having a plurality of openings of such a size as will prevent the coarse, difficultly grindable and non-grindable components of the garbage from leaving the grinding chamber, and in addition thereto having a considerably smaller number of large apertures arranged within the field of and being larger than the first mentioned openings of the screen said apertures allowing the coarse, difficultly grindable and non-grindable components to leave the grinding chamber when they by chance meet with the said apertures, a fine screen surrounding the grinding chamber and having a mesh determining the fineness of the sufficiently ground material, a casing secured to the grinding chamber and rotating therewith said casing having circumferential inlet openings communicating with the interior of the fine screen and pairs of outlet openings one outlet opening of each pair communicating with the interior of the grinding chamber while the other outlet opening of the same pair opens to the exterior of the said chamber, each pair of outlet openings being spaced from the axis of the rotary grinding chamber and so arranged as to be in a position above the axis of rotation of the grinding chamber when the corresponding inlet opening is in its uppermost position, a plurality of passages within the said casing each connecting an inlet opening of the casing with one pair of outlet openings thereof, a shiftable member arranged within and revolving with the casing and adapted to deliver the materials supplied to the casing by the fine screen to either of the outlet openings, the position of the said member determining to which of the outlet openings the materials are delivered, and a shaft secured to the said member and arranged to be operated from the outside of the casing.

10. In an apparatus of the ball mill type for grinding garbage and the like waste materials, a rotary grinding chamber having a front end plate with at least one inlet opening for supply of the materials to be ground and a rear end plate, spaced channel irons connecting the front end plate with the rear end plate and secured to the

75

said plate at the circumference thereof, spaced grid bars extending between adjacent channel irons and secured thereto, two adjacent channel irons and the grid bars between the said channel irons forming a grid section, the plurality of grid bars within the said section being arranged with such a space as will prevent the coarse, difficultly grindable and non-grindable components within the grinding chamber to leave the same, a number of grid bars within the said section each of which being swingably mounted at one end adjacent to a channel iron while the other end thereof adjacent to the following channel iron is free, means for supporting the free end of the grid bar to keep the said bar in alignment with the adjacent bars and means for moving the supporting means into a position in which the free end of the grid bar is arranged beneath the adjacent bars to provide a large aperture through which the coarse, difficultly grindable and non-grindable components may pass when they by chance meet with the said aperture.

11. In an apparatus of the ball mill type for grinding garbage and the like waste materials, a rotary grinding chamber, a coarse grid forming the circumferential walls of the said chamber the said grid having a plurality of openings of such a size as will prevent the coarse, difficultly grindable and non-grindable components of the garbage from leaving the grinding chamber, and in addition thereto having a considerably smaller number of large apertures arranged within the field of and being larger than the first mentioned openings of the grid said apertures allowing the coarse, difficultly grindable and non-grindable components to leave the grinding chamber when they by chance meet with the said apertures, a fine screen surrounding the grinding chamber and having a mesh determining the fineness of the sufficiently ground material, an elevating device rotating with the grinding chamber, the said device having circumferential openings communicating with the interior of the fine screen and at least one pair of outlet openings one outlet opening of the said pair communicating with the interior of the grinding chamber while the other outlet opening of the same pair opens to the exterior of the said chamber, adjustable means arranged within and rotating with the elevating device and adapted to deliver the materials supplied to the said device by the fine screen to either of the outlet openings of the elevating device the position of the said adjustable means determining to which of the outlet openings the materials are delivered, and a shaft secured to the adjustable means and arranged to be operated from the outside of the elevating device.

12. In an apparatus of the ball mill type for grinding garbage and the like waste materials, a rotary grinding chamber, a coarse grid forming the circumferential walls of the said chamber the said grid having a plurality of openings of such a size as will prevent the coarse, difficultly grindable and non-grindable components of the garbage from leaving the grinding chamber and in addition thereto having a considerably smaller number of large apertures arranged within the field of and being larger than the first-mentioned openings of the grid said apertures allowing the coarse, difficultly grindable and non-grindable components to leave the grinding chamber when they by chance meet with the said apertures, a fine screen surrounding the grinding chamber and having a mesh determining the fineness of the sufficiently ground ma-

terial, a casing secured to the grinding chamber and rotating therewith said casing having circumferential inlet openings communicating with the interior of the fine screen and pairs of outlet openings one outlet opening of each pair communicating with the interior of the grinding chamber while the other outlet opening of the same pair opens to the exterior of the said chamber, each pair of outlet openings being spaced from the axis of the rotary grinding chamber and so arranged as to be in a position above the axis of rotation of the grinding chamber when the corresponding inlet opening is in its uppermost position, a plurality of passages within the said casing each connecting an inlet opening of the casing with one pair of outlet openings thereof, a shiftable member arranged within and revolving with the casing and adapted to deliver the materials supplied to the casing by the fine screen to either of the outlet openings, the position of the said member determining to which of the outlet openings the materials are delivered, and a shaft secured to the said member and arranged to be operated from the outside of the casing.

13. In an apparatus of the ball mill type for grinding garbage and the like waste materials, a rotary grinding chamber having a front end plate with at least one inlet opening for supply of the materials to be ground and a rear end plate, spaced channel irons connecting the front end plate with the rear end plate and secured to the said plates at the circumference thereof, spaced grid bars extending between adjacent channel irons and secured thereto, two adjacent channel irons and the grid bars secured thereto forming a grid section, the plurality of grid bars within the said section being arranged with such a space as will prevent the coarse, difficultly grindable and non-grindable components of the materials within the grinding chamber to leave the same whereas a smaller number of grid bars within the same section are arranged with a larger space forming large apertures through which the said coarse components may slip when they by chance meet with the said apertures.

14. In an apparatus of the ball mill type for grinding garbage and the like waste materials, a rotary grinding chamber, a coarse screen forming the circumferential walls of the said chamber and acting as the grinding surface of the cham-

- ber, the said screen having a plurality of openings of such a size as will prevent the coarse, difficultly grindable and non-grindable components of the garbage from leaving the grinding chamber and in addition thereto having a considerably smaller number of large apertures being larger than the firstmentioned openings of the screen said apertures allowing the coarse, difficultly grindable and non-grindable components to leave the grinding chamber when they by chance meet with the said apertures and a fine screen for screening the material passing through the coarse screen said fine screen having a mesh determining the fineness of the sufficiently ground material.
15. In an apparatus of the ball mill type for grinding garbage and the like waste materials, a rotary grinding chamber, a coarse grid forming the circumferential walls of the said chamber and acting as the grinding surface of the chamber, the said grid having a plurality of openings of such a size as will prevent the coarse, difficultly grindable and non-grindable components of the garbage from leaving the grinding chamber and in addition thereto having a considerably smaller number of large apertures being larger than the firstmentioned openings of the grid said apertures allowing the coarse, difficultly grindable and non-grindable components to leave the grinding chamber when they by chance meet with the said apertures and a fine screen for screening the material passing through the coarse grid said fine screen having a mesh determining the fineness of the sufficiently ground material.
